Primary Examiner — Justin M Jonaitis*Assistant Examiner* — Bria' L Simmons-Holloway(74) *Attorney, Agent, or Firm* — Ricky Lam(57) **CLAIM**

The ornamental design for a car key programmer as shown and described.

DESCRIPTION

FIG. 1 is a front, right and top perspective view of a car key programmer showing my new design;

FIG. 2 is a rear, left and bottom perspective view thereof;

FIG. 3 is a front elevational view thereof;

FIG. 4 is a rear elevational view thereof;

FIG. 5 is a right view thereof;

FIG. 6 is a left view thereof;

FIG. 7 is a top plan view thereof;

FIG. 8 is a bottom plan view thereof; and,

FIG. 9 is an enlarged view of a portion labeled as "9" on FIG. 1.

The long dash-short dash broken lines depict enlargement boundaries that form no part of the claim. The evenly broken lines illustrate portions of the car key programmer that form no part of the claimed design.
